CONTAINER

Guy O. Conner, Wheeling, W. Va., assignor to
 Wheeling Steel Corporation, Wheeling, W. Va.,
 a corporation of Delaware

Application June 24, 1938, Serial No. 215,615

12 Claims. (Cl. 221—27)

This invention relates to containers and more particularly to containers which are vented to facilitate the egress of air when the container is being filled and the ingress of air when the container is being emptied. The invention is well adapted for use in connection with shipping containers for shipping liquids and having a relatively small inlet and outlet passage.

I provide a container having an inlet and outlet passage, a liquid conduit within said passage, a portion of said passage outside said conduit constituting at least in part a venting passage for the container, and means communicating with the venting passage facilitating venting of the container. Said means preferably comprise a venting conduit within the container communicating with the venting passage. A portion of the container preferably extends inwardly thereof from the inlet and outlet passage and forms the inner end of the venting passage and has an opening through which communication is afforded between the venting passage and the interior of the container.

In one of its aspects the invention is well adapted for use in connection with containers having a spout within the inlet and outlet passage movable between an inward and an outward position relatively to the interior of the container, one form of such spout being what is commonly termed a "pull-out" spout. The inwardly extending portion of the container preferably serves as a guide for the spout as well as serving the venting function above mentioned. The spout guide preferably surrounds the spout and, in addition to having said inwardly extending portion, also preferably has another portion spaced circumferentially from the inwardly extending portion terminating in a direction inwardly of the container at a point nearer the inlet and outlet passage than the first mentioned portion, whereby to provide for effective venting of the container and avoiding the trapping of air at the top of the container when the container is filled.

Other details, objects and advantages of the invention will become apparent as the following description of a present preferred embodiment thereof proceeds.

In the accompanying drawing I have shown a present preferred embodiment of the invention, in which

Figure 1 is a partial central vertical cross-sectional view through a spouted sheet metal shipping container, the cross section also being taken centrally through the inlet and outlet passage and the spout;

Figure 2 is a partial bottom plan view of the container shown in Figure 1; and

Figure 3 is a fragmentary cross-sectional view to enlarged scale showing details of the structure.

Referring now more particularly to the drawing, there is provided a sheet metal shipping container 2 having the usual outwardly rolled bead or rim 3 at its open upper end and provided therebelow with a strengthening or rolling ring 4. A cover 5 is provided which may in general be of usual construction but which is provided with my improved dispensing and venting structure. The cover 5 has a flat body portion 6 and a rim portion 7 of generally inverted U shape, such portion 7 overlying the rim 3 of the container, and a gasket 8 being interposed therebetween. The cover is a conventional lug cover, being held in place on the container by lugs 9 formed integrally with the cover and which are turned under the rim 3 of the container.

The cover 5 has a sunken portion 10 and seamed to the cover at the portion 10 by a seam 11 is an outwardly or upwardly projecting externally threaded neck 12 forming an inlet and outlet passage for the container and an inwardly or downwardly extending annulus 13 for a purpose to be described. A pull-out spout 14 is provided, such spout being guided within the neck 12 at 15 and within the annulus 13 at 16. The spout 14 is adapted to assume an inward position as shown in full lines in Figure 1 or an outward position as shown in dotted lines in Figure 1. It may be manually moved in and out within the guiding means above mentioned. A cap 17 is provided for the container and is adapted to be screwed down over the externally threaded neck 12, the skirt of the cap being internally threaded for this purpose, and the cap contains in its upper portion a gasket 18 adapted when the cap is screwed down on the neck 12 to seal the container at the sealing portion 19 thereof.

The spout 14 is of generally cylindrical shape with an outwardly rolled bead 20 at its upper extremity and an outwardly turned flange 21 at its lower extremity. The limit of inward movement of the spout is determined by engagement of the bead 20 with the portion 15 of the neck 12, and the limit of outward movement of the spout is determined by engagement of the flange 21 with the portion 16 of the annulus 13. The spout is preferably made of light gauge sheet metal and at opposed points the metal of the spout is pressed inwardly to provide opposed venting passages 22 to allow air to pass between the outside and the space between the spout and the interior

of the neck 12. This space, shown at 23 in Figure 1, may be termed a venting passage and is disposed within or forms a part of the inlet and outlet passage of the container, which is defined by the neck 12 but is outside the spout or liquid conduit 14. This venting passage 23 is, as above indicated, connected with the outside by the passages 22 formed at the outside of the spout 14 and which permit the passage of air to and from the outside between the spout and the neck 12.

10 The annulus 13 has a portion 24 which extends inwardly of the container from the inlet and outlet passage as shown in Figures 1 and 3. In the portion 24 is provided an opening 25 through which passes the end of a vent conduit or tube 26. The vent tube 26 extends thence generally transversely and upwardly within the container and has its opposite end welded or soldered to the cover at 27.

20 The lower or inner surface of the annulus 13 is inclined with respect to the axis of the spout 14 as indicated by the dotted lines 28 in Figure 1. Thus at the portion of the annulus diametrically opposite the portion 24 the annulus terminates 25 in a direction inwardly of the container at a point nearer the inlet and outlet passage than the portion 24 thereof. This construction of the annulus 13 obviates the trapping of air outside the annulus and against the inside of the top of the cover. 30 Also, as the portion 24 of the annulus 13 is nearest the center of the cover the diametrically opposed portion of the annulus is nearest the cover rim and when contents of the container are being poured out there is a minimum of interference 35 with the flow of such contents into the spout 14, which when the contents are poured out will be in its outward position as shown in dotted lines in Figure 1. It will be understood that when pouring out the contents of the container the 40 container will ordinarily be tilted toward the left viewing Figures 1 and 2 of the drawing.

A bail 29 for manipulating the spout 14 is provided near the top of the spout, such bail consisting simply of a bent piece of wire having its 45 ends serving as trunnions and passing through holes in the sheet metal spout at the opposed inwardly bent portions 22 thereof.

The container may be filled with the spout 14 in either its inward or its outward position as may 50 be most convenient. It may be filled by introducing into the top of the spout a filler tube which substantially closes the spout so that sufficient venting cannot be had through the spout itself. The introduction of liquid into the container 55 forces the air in the container upwardly where it enters the upper end of the vent tube 26. It passes through the vent tube 26 into the venting passage 23 and thence out through the passages provided by the inwardly bent portions 22 of the 60 spout 14.

When the contents of the container are being poured out the spout 14 will ordinarily occupy its outward position as shown in dotted lines in Figure 1. The liquid poured out is displaced by 65 air entering the container through the same path as above described through which the air is forced out when the container is filled except that the air passes in the opposite direction.

While I have shown and described a present 70 preferred embodiment of the invention, it is to be distinctly understood that the same is not limited thereto but may be otherwise variously embodied within the scope of the following claims.

I claim:

75 1. A container having an opening and a neck

communicating therewith, a liquid conduit within said neck, and a venting passage within said neck and outside said conduit, a portion of the container extending inwardly thereof from said neck, serving as a guide for said conduit and forming the inner end of said venting passage and having an opening through which communication is afforded between said venting passage and the interior of the container.

2. A container having an opening and a neck 10 communicating therewith, a spout within said neck movable between an inward and an outward position relatively to the interior of the container and a venting passage within said neck and outside said spout, a portion of the container extending inwardly thereof from said neck, serving as a guide for said spout and forming the inner end of said venting passage and having an opening through which communication is afforded between said venting passage and the interior of 20 the container.

3. A container having an inlet and outlet passage, a liquid conduit within said passage, a portion of said passage outside said conduit constituting at least in part a venting passage for the 25 container surrounding said conduit, a portion of the container extending inwardly of the container from said inlet and outlet passage and forming the inner end of said venting passage, and a venting conduit within the container communicating with said venting passage adjacent said inner end thereof.

4. A container having an inwardly depressed wall portion and an inlet and outlet passage thereat, a liquid conduit within said passage, a portion of said passage outside said conduit constituting at least in part a venting passage for the 35 container, and a venting conduit within the container communicating with said venting passage and extending generally upwardly and transversely of the container therefrom to a portion of the container wall removed from said depressed portion.

5. A container having an inlet and outlet passage and a spout within said passage movable 45 between an inward and an outward position relatively to the interior of the container, a portion of said passage outside said spout constituting at least in part a venting passage for the container, a portion of the container extending inwardly 50 thereof from said inlet and outlet passage, serving as a guide for said spout and forming the inner end of said venting passage and having an opening through which communication is afforded between said venting passage and the interior of the container.

6. A container having an inlet and outlet passage, a liquid conduit within said passage, a portion of said passage outside said conduit constituting at least in part a venting passage for the 60 container, and means surrounding said conduit forming the inner end of said venting passage and having a portion extending inwardly of the container from said inlet and outlet passage and having an opening through which communication is afforded between said venting passage and the interior of the container, another portion of said means spaced circumferentially from said first mentioned portion thereof terminating in a direction inwardly of the container at a point 70 nearer said inlet and outlet passage than said first mentioned portion of said means.

7. A container having an inlet and outlet passage, a liquid conduit within said passage, a portion of said passage outside said conduit constit- 75

tuting at least in part a venting passage for the container, means surrounding said conduit forming the inner end of said venting passage and having a portion extending inwardly of the container from said inlet and outlet passage, and a venting conduit communicating with said venting passage at said portion of said means, another portion of said means spaced circumferentially from said first mentioned portion thereof terminating in a direction inwardly of the container at a point nearer said inlet and outlet passage than said first mentioned portion of said means.

8. A container having an inlet and outlet passage, a spout within said passage movable between an inward and an outward position relatively to the interior of the container, a portion of said passage outside said spout constituting at least in part a vent passage for the container, means surrounding said spout and serving as a guide therefor, forming the inner end of said venting passage and having a portion extending inwardly of the container from said inlet and outlet passage, and a venting conduit communicating with said venting passage at said portion of said means, another portion of said means spaced circumferentially from said first mentioned portion thereof terminating in a direction inwardly of the container at a point nearer said inlet and outlet passage than said first mentioned portion of said means.

9. A container having an inlet and outlet passage, a liquid conduit within said passage, a portion of said passage outside said conduit constituting at least in part a venting passage for the container, and means surrounding said conduit forming the inner end of said venting passage and having a portion extending inwardly of the container from said inlet and outlet passage and having an opening through which communication is afforded between said venting passage and the interior of the container, the surface of said means facing toward the interior of the container being inclined with respect to the axis of said conduit so that another portion of said means

spaced circumferentially from said first mentioned portion thereof terminates in a direction inwardly of the container at a point nearer said inlet and outlet passage than said first mentioned portion of said means.

10. A container having an inlet and outlet passage and a spout within said passage movable between an inward and an outward position relatively to the interior of the container, a portion of said passage outside said spout constituting at least in part a venting passage for the container, there being guide means for the spout adjacent the outer extremity of said inlet and outlet passage, the spout having a depression at its exterior to provide for communication between the venting passage and the outside.

11. A container having an inlet and outlet passage in its top, a liquid conduit within said passage, a portion of said passage outside said conduit constituting at least in part a venting passage for the container, and a venting conduit within the container communicating with said venting passage at a point removed from the upper surface of the container and extending generally upwardly and transversely of the container therefrom.

12. A container having an inlet and outlet passage in its top and disposed eccentrically thereof, a liquid conduit within said passage, a portion of said passage outside said conduit constituting at least in part a venting passage for the container, and means surrounding said conduit forming the inner end of said venting passage and having a portion extending inwardly of the container from said inlet and outlet passage and having an opening through which communication is afforded between said venting passage and the interior of the container, the surface of said means facing toward the interior of the container being inclined to a plane at right angles to the vertical axis of the container and sloping generally upwardly and outwardly toward the nearest point of the rim of the top of the container.
